UNITED STATES PATENT OFFICE.

GUSTAVE E. VILLARET, OF LEONIA, NEW JERSEY, ASSIGNOR TO METROPOLITAN-COLUMBIA MFG. CO., INC., A CORPORATION OF NEW YORK.

DESIGN FOR A SHIELD PLATE FOR LIGHTING-FIXTURE BRACKETS OR ARTICLE OF ANALOGOUS NATURE.

Application filed March 28, 1929. Serial No. 30,659. Term of patent 3½ years.

To all whom it may concern:

Be it known that I, GUSTAVE E. VILLARET, a citizen of the United States, and a resident of Leonia, county of Bergen, and State of New Jersey, have invented a new, original, and ornamental Design for a Shield Plate for Lighting-Fixture Brackets or Article of Analogous Nature, of which the following is a specification, reference being had to the accompanying drawing, forming a part hereof.

In the drawing:

Figure 1 is a front elevational view of the shield plate for lighting fixture brackets or

article of analogous nature, the part shown in full line outline being ornamented in the same manner as the part more fully illustrated; and

Figure 2 is a diagrammatic side outline view of the same.

I claim:

The ornamental design for a shield plate for lighting fixture brackets or article of analogous nature substantially as shown and described.

GUSTAVE E. VILLARET.
